FOREIGN PATENT DOCUMENTS

EP 2387880 3/2013

Primary Examiner — George D. Kirschbaum*Assistant Examiner* — Clesce Moore, Jr.(74) *Attorney, Agent, or Firm* — Marsh Fischmann & Breyfogle LLP; Russell T. Manning(57) **CLAIM**

The ornamental design for the fishing paddle, as shown and described.

DESCRIPTION

FIG. 1 is perspective view of the fishing paddle;
 FIG. 2 is top view of the fishing paddle;
 FIG. 3 is a bottom view of the fishing paddle;
 FIG. 4 is a side view of the fishing paddle; and,
 FIG. 5 is a side view of the fishing paddle.

The broken lines shown illustrate portions of the fishing paddle that form no part of the claimed design.

1 Claim, 5 Drawing Sheets(56)
